UNITED STATES PATENT OFFICE.

EDWARD FOOSE, OF WASHINGTON, DISTRICT OF COLUMBIA.

SHEET-METAL CABINET AND LOCKER.

Application filed May 21, 1923. Serial No. 640,584.

To all whom it may concern:

Be it known that I, EDWARD FOOSE, a citizen of the United States, and resident of the city of Washington, District of Columbia, 5 have invented new and useful Improvements in Sheet-Metal Cabinets and Lockers, of which the following is a specification.

This invention relates to improvements in construction of sheet metal cabinets and 10 lockers arranged side by side, and the principal objects of the invention are to provide interchangeable parts and parts continuous over several compartments that can be constructed economically, assembled 15 conveniently and that will be strong, and neat in appearance with a minimum of rivets and bolts in the exposed parts thereof.

A preferred embodiment of my invention is shown in the accompanying drawings, in 20 which—

Figure 1 is a horizontal section through a group of lockers;

Figure 2 is a vertical section on the line 2—2 of Figure 1, enlarged;

Figure 3 is a vertical section on the line 3—3 of Figure 1, enlarged;

Figure 4 is a perspective view of a bottom plate;

Figure 5 is a fragmentary of a base unit;

Figure 6 is a front elevation showing two end sections of a row of lockers;

Figure 7 is a horizontal section of one wall unit;

Figure 8 is a fragmentary section of a front base member; and

Figure 9 is a fragmentary section of a back base member.

In Figures 1 and 2 are shown construction details of lockers of the back to back type.

40 In Figure 1 a horizontal section through a group of lockers of this type showing the several wall units required for a group and the way they are connected together. It is understood that the number of locker units in a group will vary according to conditions to be met. All wall units will be made of metal.

The principal wall member, a horizontal section of which is shown in Figure 7, comprises a back 1, a partition 2, and a stile 3, all made of one piece of sheet metal, except the reinforcing bar of stile. Back 1 is made of such a width in relation to width of locker as to allow for lap on one end over back of adjoining wall member. At the 55 other end of back an offset 4 is formed by

bending the back inwardly the thickness of the metal of which it is made, said offset 4 being slightly larger than lap of adjoining back, and parallel with same. Partition 2 60 is bent at a right angle to back 1, then metal is bent inwardly at three right angle bends in the same direction around a reinforcing bar 5 to form stile 3. Sheet metal part of said stile is secured to bar, preferably, by rivets or bolts 6 passing through hinge 7 and by such other means as may be desired.

An end wall 8 is formed with flange 9 at one end and stile 10 at the other end; 70 said stile is formed by bending metal at three right angle bends around a reinforcing bar 5 and securing same by rivets, bolts or other means.

Back to back lockers are formed by the 75 use of auxiliary partitions 11 made with a flange 12 at one end, and a stile 3 at the other end, said stile is formed like stile 3 on principal wall member. This second row of lockers has auxiliary end walls 13 at each 80 end with flange 12 and stile 3 as described heretofore. Auxiliary partitions and auxiliary end walls are connected to principal wall members and secured by bolts 14.

A base unit for a group of lockers of the 85 back to back type comprises front plates 15 and intermediate plate 16 connected together by angle braces 17 spaced, preferably under every second partition, and secured by bolts 18 or other means. Said angle braces 90 have screws 19 on the under side of lower flange for adjustment to floors that are out of level. End plates 20 may be used on ends exposed to views. These plates 15, 16 and 20 are preferably, made of steel bars, and angle braces 17 of rolled steel angles. It is understood that the base unit may be constructed differently from the one described and illustrated. A modified form of construction would be to make the front plate 15, intermediate plate 16 and end plates 20 100 of one bar with a welded joint, and small flanges welded on to be tapped for screws in place of angle braces 17. A base for a double row would be made by adding a 105 U shaped integral part comprising the front 15 and parts of sides 20 with means for bolting this to the four sided base unit for a single row. Floor beads 21 of wood or steel 110 may be used to make a right joint at junction of base and floor.

Floor plate 22 for a group of lockers of

- the back to back type is of sheet metal and shaped with a longitudinal channel 23 to receive backs 1, and with latitudinal or cross channels 24 to receive partitions 2 and 11. 5 Said channels are spaced directly under backs and partitions, and are of a width equal to thickness of backs and partitions. Channels will be of suitable depth to hold backs and partitions securely in place.
- 10 Bolts, or other means, passing through channels and inserted part may be used to hold these parts together. At outer edges of floor plate pendant flanges 25 will be formed at a right angle to plate, which flanges will 15 engage clips 26 secured to base members by spot welding or otherwise. A clip 27 on intermediate plate 16 will support longitudinal channel. Two clips 26 should preferably be used under each flange, and two clips 20 27 under each section of channel being approximately of a length equal to the width of a locker. Floor plate will be punched at intersection of channels prior to forming same, and will be notched to fit around 25 stiles 5.

For ceiling of lockers a reversed floor plate 22 will be used, which will be fastened to upper part of back 1 and partitions 2 and 11 in similar manner to that specified for 30 floor plate. Flanges along outer edges of ceiling, corresponding to pendant flanges of floor plate, will engage clips 28 which are secured to cap 29.

Cap 29 may be a plain metal bar or angle 35 or shaped with a molded profile as desired; it will be continuous over a series of lockers and secured to each stile 3 by a bolt 30. A cover plate 31 may be applied to top of lockers if desired, held in position by clips 32 to 40 cap 29 and supported over backs by a U-shaped support 33 spaced apart at such distances as will prevent excessive sag in cover plate.

The doors 34 shown on drawing are of the 45 plate type made of a steel plate applied on the outside of stile 3 with hinges, and provided with lock 35 engaging locker at one or more places.

It is evident that this construction is suitable for a single row of lockers as well as for 50 a double row of the back to back type, and that similar advantages of construction and assembling accrue from the use of the shaped parts illustrated and described here- 55 tofore. If built as a single row of lockers the intermediate plate 16 would become a back plate member, the floor plate 22 and the corresponding ceiling plate could be made either with the longitudinal channel 60 23 as its back edge, or with a flange as its back edge similar to flanges 25 on front of floor plate, and cover plate 31 would be approximately half the width required for a double row, supported at back by turning U 65 support 33 sidewise or by some other means.

Auxiliary partitions 11 and auxiliary end wall 13 would of course, be omitted.

From the drawings and the foregoing description it is manifest that there will be a minimum of rivets and bolts in the interior of the lockers for an assembled locker of the knock-down type; that is, a locker that may be shipped or moved in parts and put together at the place of installation, because most of the bolts will be concealed below the 70 floor plate or above the ceiling plate. There will be also, a minimum of parts as many of the individual parts are applied to, and form a part of a plurality of lockers. It can readily be seen that the base unit being continuous under a plurality of lockers and the cap member extending over a similar number of lockers makes for rigidity in construction and neatness in appearance, eliminating joints and cover pieces over joints and at 75 the same time, provides these members in a form that they can be conveniently transported and handled.

Having described my invention what I claim is:—

1. A sheet metal structure comprising integral wall elements, each of said wall elements composed of a back and a side, said side being bent inwardly from the back, an offset portion formed along one edge of the 80 back, said portion being offset for a distance equal to the thickness of the sheet metal forming the back whereby adjoining back walls are aligned, and means for securing each 85 wall element to its adjoining wall element for forming a series of compartments.

2. A sheet metal structure comprising integral wall elements, each of said wall elements composed of a back and a side, said side being bent inwardly from the back, an offset portion formed along one edge of the 90 back, said portion being offset for a distance equal to the thickness of the sheet metal forming the back whereby adjoining back walls are aligned, and means for securing each 95 wall element to its adjoining wall element for forming a series of compartments, and partitions and end walls fastened to the back of the wall elements for forming a second series of compartments.

3. A sheet metal structure comprising integral wall elements, each of said wall elements composed of a back, a side and a stile, said side being approximately at a right angle to the back, said stile being approximately at a right angle to the side, an offset portion formed parallel with and along one edge of back, said portion being offset for a distance equal to the thickness of the sheet metal forming the back whereby adjoining back walls are aligned, and means for securing one wall element to an adjoining wall element for forming compartments.

4. A sheet metal structure, including a plurality of compartments, comprising in- 130

- tegral wall elements, each of said wall elements composed of a back, a side bent inwardly from the back, the back having the portion next the side offset inwardly to provide a rabbet for the reception of the free edge of the adjoining back, and a stile bent inwardly from the side, means for securing each wall element to its adjoining wall element, and a door hinged to a stile of each wall element and engaging the stile of an adjoining wall element when closed.
5. A metal structure including a plurality of lockers consisting of wall elements, each having a back and an integral side arranged at right angles to the back, the metal at the junction of the back and side being offset to provide a rabbet for the reception of the free edge of the adjacent back, and a stile bent inwardly from said side; means on the base frame for receiving the locker wall elements and a cap unit connected with the stile of each said integral wall element.
10. In a metal structure, the combination of a base frame, a plurality of integral locker wall elements each comprising a back, a side bent inwardly from said back, the back having the portion next the side offset inwardly to provide a rabbet for the reception of the free edge of the adjacent back, and a stile bent inwardly from said side; means on the base frame for receiving the locker wall elements and a cap unit connected with the stile of each said integral wall element.
15. A metal structure including a plurality of lockers consisting of wall elements, each having a back and an integral side arranged at right angles to the back, the metal at the junction of the back and side being offset to provide a rabbet for the reception of the free edge of the adjoining back, and a stile bent inwardly from the side, means for securing each wall element to its adjoining wall element, and a door hinged to a stile of each wall element and engaging the stile of an adjoining wall element when closed.
20. In a metal structure, the combination of a base frame, a plurality of integral locker wall elements each comprising a back, a side bent inwardly from said back, the back having the portion next the side offset inwardly to provide a rabbet for the reception of the free edge of the adjacent back, and a stile bent inwardly from said side; means on the base frame for receiving the locker wall elements and a cap unit connected with the stile of each said integral wall element.
25. In a metal structure, the combination of a base frame, a plurality of integral locker wall elements each comprising a back, a side bent inwardly from said back, the back having the portion next the side offset inwardly to provide a rabbet for the reception of the free edge of the adjacent back, and a stile bent inwardly from said side; means on the base frame for receiving the locker wall elements and a cap unit connected with the stile of each said integral wall element.
30. EDWARD FOOSE.
